UNITED STATES PATENT OFFICE.

FRIEDRICH MÜLLER, OF HARTFORD, CONNECTICUT, ASSIGNOR TO PRATT & WHITNEY COMPANY, OF NEW YORK, N. Y., A CORPORATION OF NEW JERSEY.

MECHANICAL MOVEMENT.

Original application filed March 31, 1919, Serial No. 286,524. Divided and this application filed July 29, 1920. Serial No. 399,715.

To all whom it may concern:

Be it known that I, FRIEDRICH MÜLLER, a citizen of the United States, residing at Hartford, in the county of Hartford and State of Connecticut, have invented certain new and useful Improvements in Mechanical Movements, of which the following is a specification.

In my copending applications for metal cutting machines, Serial No. 201,338, filed Nov. 10th, 1917, and Serial No. 286,524, filed March 31st, 1919, I have shown and described metal cutting machines particularly adapted for shaping and preferably relieving rotatable work, such as blanks for milling cutters. Certain features of the said machines are adapted for use for other classes of work and are novel when considered broadly as mechanical movements.

In accordance with the present invention, a tool (illustrated as a cutting tool) is movable with respect to a holder (illustrated as a work-holder mechanism) and certain improved devices are used for controlling the tool movement. Relative movement is effected between the tool and the holder, and, as illustrated, the tool is moved. Preferably the tool is moved intermittently rather than continuously so that it successively assumes different relatively fixed positions. Relative separation or withdrawal takes place between the tool and the holder at intervals, and, as illustrated, the tool is withdrawn. Preferably the tool is withdrawn at the time of each movement. Also by preference mechanism such as a guide or former and a pin cooperating therewith is provided for controlling the successive positions of the tool. Relative movements take place between the pin and the guide or former similar to those between the tool and the holder.

Mechanism is provided which is preferably independent of or supplemental to the with-

drawing mechanism for returning the tool and usually the pin to operative positions. This mechanism preferably serves to return the tool and pin slowly with a minimum pressure. It is also preferred to provide an improved locking means for holding the tool and usually the pin in their operative positions. This locking means is particularly useful in combination with the independent returning mechanism.

The general object of the invention is to provide a mechanical movement capable of controlling the relative movements and preferably the movements of the tool and the pin in the ways above outlined. Further and more specific objects will be apparent from the following specification and claims.

In the accompanying drawings the invention is illustrated as embodied in a metal cutting machine such as presented in my aforesaid application, Serial No. 286,524. It will be understood, however, that the metal cutting machine is shown and described merely for convenience and that the invention is capable of being embodied in machines structurally different and adapted for different classes of work. The drawings, therefore, are not to be construed as defining or limiting the scope of the invention, the accompanying claims being relied upon for that purpose.

Of the drawings:

Figures 1 to 4 are diagrams illustrating the essential characteristics of a mechanical movement embodying the invention.

Fig. 5 is a fragmentary front view, partly in section, of a metal cutting machine including a mechanical movement embodying the invention.

Fig. 6 is a fragmentary plan view of the machine shown in Fig. 5.

Fig. 7 is a vertical transverse sectional view taken along the line 7—7 of Fig. 5.

Fig. 8 is a vertical transverse sectional view taken along the line 8—8 of Fig. 5.

Fig. 9 is a fragmentary vertical longitudinal sectional view taken along the line 9—9 of Fig. 8.

Fig. 10 is a fragmentary vertical longitudinal section taken along the line 10—10 of Fig. 7.

In the diagrammatic Figs. 1 to 4 I have illustrated the essential principles of a mechanism embodying the invention. In these views, F represents a guide, pattern or former having a shape or contour which is to be followed. P is a follower or pin which is adapted to engage the former and to follow the shape or contour thereof. Preferably there is provided a tool T which is adapted to be controlled by the former and pin, this tool preferably being connected with the pin to be bodily movable therewith. As illustrated, both the pin P and the tool T are mounted on a support S. When there is a tool such as T there is also provided a carrier or holder which is adapted to hold the work to be operated upon by the tool. The tool T may be a cutting tool, but the invention is not so limited as the tool may be one adapted for scribing or otherwise acting upon the work.

In accordance with the invention, relative longitudinal movement is effected intermittently or at intervals between the former and the pin. Preferably the pin is moved with respect to the former though this is not essential. The former and the pin are transversely separated at the time of each longitudinal movement. Preferably the pin is withdrawn from the former, the former remaining stationary, but it will be understood that this is not essential. At the conclusion of each relative longitudinal movement the former and pin are restored to engagement, contact being effected at a new location on the former.

When a tool such as T is provided relative movements between the tool and the holder are effected which are similar to those between the pin and the former. When the longitudinal and withdrawing movements are imparted to the pin and the former remains stationary similar movements are imparted to the tool and the holder remains stationary.

Fig. 1 illustrates the pin P in engagement with the former F and the tool T in operative relationship with the holder H. Fig. 2 illustrates the pin and the tool withdrawn preparatory to a longitudinal movement. Fig. 3 shows the pin and tool still withdrawn but moved longitudinally to a new position. Fig. 4 shows the pin and the tool restored to operative positions, the pin contacting with the former at a new location on the contour and the tool having a corresponding new position with respect to the holder. It will be understood that the movements as illustrated in Figs. 1 to 4 are considerably exaggerated and that in practice they would be much smaller in order that the successive positions of the pin and tool along the respective contours might be very close together.

It will be seen that this construction makes

it possible to follow a contour having portions thereof very steeply inclined. In earlier machines making use of a former and pin it has been customary to feed the pin longitudinally at a constant slow speed. The pin has been held in engagement with the former by spring pressure or otherwise and the expectation has been that the pin would automatically follow the inclined parts of the contour, moving inward or outward in accordance therewith. Machines of this type have been successful to a limited extent but it has been impossible for them to follow a contour in which parts thereof were sharply inclined. It is clear that in a machine of the earlier type the pin P would fail to follow outward along a sharply inclined part of the contour and would bind, thus resulting in the stopping or breaking of the machine. Even when the contour was not so steep as to completely bind the pin there was nevertheless a strong side pressure applied to the pin which tended to deflect or distort it, thus interfering with the accuracy of the operation. All of these difficulties are overcome in a machine constructed in accordance with my invention. The pin and the former and also the tool and the work are separated at the time of longitudinal movement and thus longitudinal movement can take place freely without any hindrance. At the conclusion of longitudinal movement the pin is restored to engagement with the former at a new transverse location corresponding to the new longitudinal location.

Figs. 5 to 10 of the drawings show a machine embodying the principles illustrated in Figs. 1 to 4 and also having many additional features. In these figures, 1 represents the main frame or bed upon which the other parts of the mechanism are supported. Mounted preferably in fixed position on the frame is a carrier or holder which is illustrated as being a work-holding means preferably adapted to permit the work or blank to rotate. As illustrated, the work or blank holder includes a headstock 2 and preferably also a tailstock 3. A tool holding and operating mechanism is provided as shown at 4. The tool is ordinarily associated with the holder as shown and when the holder is a work-holding means the tool is adapted to engage and usually act upon the work. In a machine such as illustrated the tool is adapted to cut the work to remove metal therefrom. Preferably the headstock 2 and the tailstock 3 are so arranged as to hold the blank against longitudinal movement, the tool mechanism 4 being moved longitudinally along the blank in the manner to be presently set forth. When the machine is so constructed, the headstock 2 is fixedly secured to the bed, preferably being formed in part integrally therewith, as shown. The

tailstock 3 is adjustable along the bed to accommodate blanks or blank arbors of different lengths.

The headstock 2 is provided with a rotatable spindle 5 mounted in bearings 6 and 7. Secured to the spindle is a collet chuck 8 which may be of any usual or preferred form and which is adapted to grip either the shank of the tool to be formed and relieved 10 or an arbor upon which the tool is mounted. As illustrated, there is a blank A mounted upon an arbor B, the arbor being engaged by the chuck 8. For rotating the spindle 5 there is provided a drive mechanism including a driving member in the form of a worm wheel 9 meshing with a worm (not shown) on a transverse rotatable shaft 11.

The tailstock 3 may be of any usual or preferred construction, and only a fragment 20 thereof is shown in the drawings. It is adjustable along ways 12 and 13 and can be secured in adjusted position by means of a suitable clamp not shown. The tailstock spindle is indicated at 16 and carries a center 17. The spindle can be moved longitudinally by means of a suitable screw. For clamping the sleeve in adjusted position there is provided a handle 20. As shown in Fig. 6, the center 17 is adjusted into engagement with the end of the arbor B.

The tool mechanism 4 includes a carriage 21 which is longitudinally movable along ways 22 and 23 on the bed 1. Mounted for transverse movement with respect to the carriage 21 is a slide 24, this slide carrying the before mentioned tool. As already stated, a metal cutting tool is illustrated but it is to be understood that the present invention is not limited to the metal cutting art. When 40 a metal cutting tool is provided, such as shown at 25, it is preferably very narrow, but if desired a wider tool may be used.

A mechanism embodying the invention is adapted for following any desired path which 45 may be a straight line or which may be a predetermined contour differing from a straight line in any practical desired way. In the case of rotary work, as illustrated, the blank may be cut with a uniform diameter or with 50 a diameter varying uniformly from end to end or it may be cut with any predetermined contour differing from a straight line. The predetermined path is followed by properly controlling the longitudinal movements of 55 the carriage 21 and the transverse movements of the slide 24. Preferably for regulating and controlling these movements I provide a former or guide and a suitable pin associated therewith, one carried in 60 fixed position on the bed 1, and the other carried by the slide 24. It will be seen that I have thus provided two supports to which the guide and the pin respectively are normally fixedly secured and whereby their relative movements are limited to two direc- 65

tions at an angle (preferably a right angle) to each other. As illustrated, there is provided a former 26 carried by the bed and a former pin 27 carried by the slide 24. The former 26 has exactly the same contour with 70 which the blank is to be formed and the former pin 27 has exactly the same shape as the cutting tool 25. The pin is detachably secured to the slide so that it can be removed and another pin be substituted correspond- 75 ing to a tool differing in shape from the tool 25 which is shown. For supporting the former 26 there is provided a bracket 28 rigidly secured to the bed 1. In order to permit adjustment, the former 26 is secured 80 to a slide 29 which is longitudinally movable along a suitable guideway 30 on the bracket, a screw 31 being provided for effecting longitudinal movement. The slide can be locked in adjusted position by means of screws 32, 85 32 engaging a gib 33. To permit the ready attachment of the former, the slide 29 is provided with a T-slot 34 adapted to receive T-bolts 35 passing through the former. To further assist in holding the former in place 90 and to prevent any possible free movement thereof, there is provided a hooked bolt 36 which, when tightened, serves to draw the former back against a suitable shoulder on the slide. In practice, a former 26 is selected 95 having a contour corresponding with the predetermined path which the tool is to follow. As illustrated, this contour is that with which the blank A is to be formed. After the former has been selected it is preferably 100 adjusted longitudinally by means of the slide 29 until it bears the same relation to the former pin 27 that the blank A bears to the tool 25. As the carriage is moved longitudinally the slide 24 with the tool 25 is 105 moved transversely so as to keep the former pin in engagement with the former.

Preferably, as illustrated, the tool is movable with respect to the slide 24 and for some classes of work such as the making 110 of blanks for milling cutters it is necessary to automatically move the tool with respect to the slide 24 during the operation of the machine. In the making of milling cutters the tool is regularly moved in such a 115 way as to properly relieve the several teeth on the blank. Mounted on the slide 24 is a slide 37 which is transversely movable along a suitable guideway. Carried in part by the slide 24 is a mechanism for effecting regular reciprocating relieving movements of the slide 37 and the tool in suitable timed relation with the rotative movement of the blank. In order that the tool may be adjusted for blanks of different sizes, there is provided a tool-carrying slide 38 transversely movable on the slide 37. For moving the slide 38 there is provided a screw 39 rotatable by means of a hand wheel 40. The slide 38 is provided 120

with a transverse T-slot 41 and a tool post 42 is held in place by means of T-bolts 43 entering the slot. The tool post has a tool-receiving aperture provided with a horizontal top wall 44 exactly at the level of the axis of the blank. The tool 25 is put in place with its top surface engaging the horizontal wall 44 of the tool post and is held in this position by means of a wedge 45.

It will be observed that with the construction described the tool is maintained in parallelism as it moves longitudinally for feeding or inward and outward to follow the contour.

The relieving mechanism for moving the slide 37 together with the tool 25 includes a rotatable relieving cam 46 which is mounted on the slide 24 so as to be bodily movable therewith. As shown, the cam is mounted on a longitudinal rotatable shaft 47 mounted in bearings 48 and 49 on a bracket 50 depending at the front of the slide 24. A lever 51 is pivoted between its ends on the slide 24 and at its lower end is provided with a roller engaging the cam 46. The upper end of the lever engages an abutment 52 on the slide 37. A coil spring 53 is interposed between the slide 37 and the slide 24, this spring tending to press the slide 37 forward, thus holding the abutment 52 in firm contact with the upper end of the lever 51. It will be seen that when the cam 46 is rotated the lever 51 will be oscillated, thus giving a reciprocating movement to the slide 37 and to the tool 25. The shape of the cam 46 is such that the slide 37 is moved forward relatively slowly at a uniform rate so that the tool may effect a relieving cut, and is then drawn back relatively rapidly so as to withdraw the tool and position it for another cut.

As before stated, the cam 46 is driven in timed relation with the blank rotation. For rotating the cam, I make use of the aforesaid transverse shaft 11. Positioned immediately below the shaft 11 is a shaft 54 which is mounted partly in the main frame and partly in a bracket 55 secured thereto. For connecting the two shafts 11 and 54 there is provided a gear 56 on the shaft 11, a gear 57 on the shaft 54 and an idler gear 58 meshing with the two gears 56 and 57. The idler gear is mounted on a bearing stud 59 carried by an adjustable slotted arm 60. The speed ratio between the two shafts 11 and 54 can be changed by removing one or both of the gears 56 and 57 and substituting other gears of different diameters, it being clear that the idler gear 58 can be adjusted to mesh with such differently diametered gears. Mounted in the said bracket 55 is a vertical shaft 65 and this shaft is driven from the shaft 54

by means of bevel gearing 63. By means of bevel gearing 64 the shaft, which is operated by the gearing 63, serves to drive a longitudinal splined shaft 65. This shaft is supported partly in a bearing 66 secured to the bed and partly in bearings 67 in a depending bracket 68 secured to the carriage 21.

Mounted on the shaft 65 between the bearings 67 and splined to the shaft, is a worm 69. This worm meshes with a worm wheel 70 which is connected with a transverse shaft 71. The worm wheel and the shaft are rotatably mounted in a bearing 72 formed in the bracket 68, and in a bearing 73 formed on a supplemental bracket 74 secured to the bracket 68. Slidably mounted on the shaft 71 is a bevel gear 75, and this gear is engaged by a bearing 76 on the aforesaid bracket 50 depending from the front end of the slide 24. The bevel gear 75 meshes with a bevel gear 77 on the shaft 47. The bevel gear 75 and the shaft 71 are splined or otherwise suitably constructed so that the bevel gear is rotated, but is at the same time free to move transversely of the machine when the slide 24 is moved. Inasmuch as the bevel gears 75 and 77 are both supported by the bracket 50, they are at all times held in mesh. It will be seen that with this construction power is transmitted from the shaft 11, through the several parts that have been described, to the shaft 65, and is transmitted from the shaft 65 to the shaft 47 and the cam 46, the connection between the shaft 65 and the shaft 47 being such that free transverse movement of the cam and associated parts is permitted. The cam 46 is given one complete rotation for each tooth of the blank. The machine can be adjusted for blanks with different numbers of teeth by changing the gears 56 and 57 as already explained.

The machine illustrated is adapted for relieving blanks with helical teeth. This feature of the machine constitutes no part of the present invention but it will be briefly described in order to give a complete understanding of the mechanism. In order that blanks with helical teeth may be properly relieved, it is necessary to effect the relieving movements of the tool in peculiar relation to the rotative movement of the blank so that the relief may be in conformity with the helical teeth. I have stated that the relieving movements of the tool are effected in timed relation to the rotative movement of the blank; and, for any given position of the carriage, this timed relation is fixed and definite, but when the carriage is moved to bring the tool into a new cutting position, it is necessary to vary the relation between the relieving movements of the tool and the rotative movement of the blank.

In the construction illustrated, the worm 9 is not connected directly with the spindle 5 but is connected indirectly by means of suitable gearing 78 which can be supplementally moved to change the spindle rotation. By preference, this gearing is bodily rotatable and includes a rack and pinion, the rack being longitudinally slideable in accordance with the longitudinal movements 10 of the carriage 21. Coaxially mounted with the spindle 5 is a sleeve 79, this being supported in bearings 80 and 81 in the headstock. The inner end of the sleeve preferably extends into and has a bearing in the outer end of the spindle. The aforesaid worm 9 is rigidly secured to the sleeve 79. Associated with the spindle is a frame 82 which is recessed to receive the outer end of the spindle and engage the outer surface 15 thereof. Slidably mounted in the sleeve 79 is a shaft 83 having rack teeth formed thereon at 84. The shaft 83 is splined to the sleeve 79 so as to be rotatable therewith. Rotatably mounted in bearings in the frame 20 82 is a transverse shaft 85 provided with teeth 86 which meshes with the rack teeth 84. Also rotatably mounted in the frame 82 is a transverse shaft 87. The two shafts 85 and 87 are connected by spur gears 88 and 30 89. Also rotatably mounted in the frame 82 is a third rotatable shaft 90, to which is secured a worm 91. This worm meshes with worm teeth 92 formed in the periphery of the spindle 5 near the end thereof. At the 35 side of the bracket 82 opposite from the gears 88 and 89 there is provided gearing (not shown) for connecting the shafts 87 and 90.

Carried by the shaft 83 at the outer end 40 thereof is an annularly grooved collar 100. Rigidly secured to the main frame adjacent the shaft 83 is a longitudinal guide stud 101. Slidably mounted on the stud 101 is a bracket 102 having a form 103 entering the 45 aperture in the collar 100. The bracket 102 is apertured to receive a longitudinal rod 104, which is connected at its right-hand end with the carriage 21. The bracket 102 can be clamped to the rod 104 in any desired 50 relative position.

It will be seen that when the carriage 21 is moved longitudinally along the bed the rod 104, together with the bracket 102, will be moved at the same time and to the same 55 extent. By reason of the engagement of the fork 103 with the collar 100 the shaft 83 is similarly moved, thus moving the rack teeth 84. When the rack slides longitudinally the pinion 86 is turned and this serves, by 60 means of the gearing and the several shafts that have been described, to turn the worm 91. The rotative movement of the worm 91 serves to turn the spindle 5 relatively to the frame 82 and the spindle 79. It will be understood, as before stated, that the entire 65

gearing 78 rotates bodily with the spindle 79. It will therefore be clear that the relative movement of the spindle with respect to the sleeve simply serves to either increase or decrease the spindle rotation to a certain extent. However, the relative movement of the spindle is determined by the longitudinal movement of the rack 84, which in turn is determined by the longitudinal movement of the carriage 21 and of the cutting tool 25 70 75 carried thereby. Inasmuch as the relieving cam reciprocates the tool with a frequency which is normally uniform, and inasmuch as the spindle and the blank are given a changed rotation which is in exact proportion to the longitudinal movement of the carriage and the tool, it is clear that the relieving movements are effected in such relation to the blank as to be in conformity with helical teeth. 80 85

For moving the carriage longitudinally along the bed there is provided a screw 107 which engages a nut 108 carried by a bracket 109 depending from the carriage. The screw is supported at its left-hand end in a bearing 110 formed in a bracket 111 secured to the bed. Mounted in the bracket 111 is a transverse shaft 112 which is connected with the screw 107 by means of bevel gearing 113. At the front end of the shaft 112 is a hand wheel 114 by means of which the screw may be turned manually to move the carriage. In order that the carriage may be moved automatically to feed the tool from one cutting position to another, a suitable mechanism is provided. This mechanism is adapted to feed the carriage intermittently. Mounted in the bracket 111 is a transverse bearing pin 115 upon which is mounted a gear 117 which meshes with a gear 118 on the shaft 112. Connected with this gear 117 is a ratchet wheel 119. Loosely mounted on the hub of the ratchet wheel is a swinging arm 123. Pivotedly connected with this arm near the lower end 95 thereof is a link 124 which is adjustably connected at its left-hand end with an oscillating crank arm 125. The crank arm is secured to a transverse rock shaft 126 which carries at its rear end a lever 128. Carried 100 by the lever at the upper end thereof is a roller positioned to be engaged by a cam 130 on a longitudinal rotatable shaft 131. Mounted on the swinging arm 123 is a ratchet 133 adapted to engage the ratchet 110 wheel 119. The shaft 131 is rotated in the manner to be presently described, and it will be seen that at each rotation thereof the arm 128 and the crank arm 125 are oscillated. By means of the link 124 the 115 oscillation of the crank arm 125 is transmitted to the plate 123, the extent of oscillation of the plate being adjustable by changing the connection between the link 120 and the crank arm. By means of the 125 130

ratchet 133 the ratchet wheel 119 is turned through a small angle, thus turning the shaft 112 and the lead screw 107 and moving the carriage.

5 Although constituting no part of the present invention the machine preferably includes two alternately operable mechanisms, one for turning the spindle and reciprocating the tool for effecting relief, and the other 10 for feeding the tool. These mechanisms are not herein shown or described in detail. It is desirable to feed the tool longitudinally while out of engagement with the blank, that is, when the tool is opposite the groove 15 between two teeth of the blank. The blank is turned through approximately one revolution and is preferably mounted in the spindle so that at the position of stopping the tool will be opposite a groove. The grooves 20 are helical but the spindle and the blank are supplementally turned at each longitudinal movement, this supplemental turning exactly compensating for the inclination of the grooves and insuring the stopping 25 of the blank with a groove opposite the tool.

Preferably the tool is withdrawn at the time of each longitudinal movement, the former pin also being withdrawn from engagement with the former. This withdrawal is effected by mechanism operated by the shaft 131, which operates intermittently, the withdrawal being properly timed with respect to the feeding movement. Associated with the slide 24 is an abutment 180 which is engaged by the upper end of a lever 181 longitudinally pivoted to the carriage 21. The lower end of the lever is provided with a roller which is adapted to be 30 engaged by a cam plate 182 on a cam disk 183 secured to the shaft 131. At the beginning of the rotation of the shaft 131 the cam plate 182 engages the roller on the lever 181 and swings it in the counter-clockwise 35 direction, thus moving the abutment 180 together with the slide 24 toward the front. In this way the tool 25 is withdrawn from the blank and the former pin 27 is withdrawn from the former 26. As the shaft 40 131 continues to rotate, the cam 180 operates the feeding mechanism in the way already described, and the carriage is moved longitudinally along the bed. After that the cam plate 182 permits the lever 181 to return 45 to the position shown, and the slide 24 moves rearward permitting the tool 25 and the former pin 27 to move to their operative positions. It will be seen that by thus withdrawing the former pin from the former 50 at the time of longitudinal movement, I avoid any difficulties incident to forcing the former pin along the former while in contact therewith. If the former pin were maintained in contact with the former at 55 all times difficulty would be experienced in

effecting the longitudinal movement, particularly at places where the contour of the former is sharply inclined. For steep inclines such as herein illustrated, it would be impossible to thus move the former pin. 70

Preferably the former pin is restored to engagement with the former by a relatively slow movement with a minimum of pressure, so that there will be no tendency to bend or distort the pin or to secure uneven contact between the pin and the former. For this purpose I provide a mechanism for returning the carriage which is entirely independent in its operation from the mechanism for withdrawing it. The before mentioned abutment 180 is not connected directly to the slide 24 but is connected to a second slide 184 which is transversely movable independently of the first slide 24. Springs 185 are interposed between the slide 184 and the carriage 21 and these springs tend to move the slide 184 rearward, thus holding the abutment 180 at all times in engagement with the lever 181. 80

The two slides 24 and 184 are ordinarily 90 connected by a lock. As shown most clearly in Fig. 9, the lock includes a plate 186 located in a recess in the top of the slide 24. The plate is provided with a boss which projects downward through a slot in the slide, 95 and threaded into this boss is a vertical stud 187. This stud extends through and closely fits an aperture in the slide 184. Pivoted to the slide 184 are two small bell-crank levers 188, these levers having horizontal upper arms which engage a collar on the stud 187. The lower ends of the levers are adapted to be engaged by a tapered cam bushing 189 vertically movable on the stud. When the bushing 189 is in its lower position, as 100 shown, the levers 188 are forced outward, thus drawing the stud 187 downward and forcing the plate 186 into clamping engagement with the slide 24. In this way the slide 24 is firmly connected with the slide 184. 110 When the bushing 189 is in its raised position, the levers 188 swing inward, thus permitting the stud 187 to move upward and release the plate 186 from its clamping engagement with the slide 24. For moving 115 the bushing 189 there is provided a forked lever 190 having projections engaging slots or notches in the bushing. This lever is secured to a longitudinal rock shaft 191 mounted in bearings in the carriage 21. 120 Connected with the lever 190 is a lever 192 having a roller which is adapted to be engaged by cam plates 193 and 194 secured to a cam disk 195 mounted on the shaft 131. It will be seen that as the shaft 131 rotates, 125 the cam plate 193 engages the roller on the lever 192, thus moving the lever 190 and the cam bushing 189 upward and releasing the lock. Subsequently the roller is engaged by the cam plate 194, thus moving the cam 130

bushing 189 downward and re-engaging the lock.

I have already stated that a supplemental mechanism is provided for returning the slide after it has been withdrawn in the way before described. Preferably, in order that this supplemental returning mechanism may operate without being affected in any way by the return movement of the slide 184, and in order further that the slide 24 may be returned with a minimum of effort, I provide a supplemental means for supporting the slide 24 after it has been unlocked from the slide 184. As illustrated, the carriage 21 is provided near its front and rear with transverse pivot pins 196 and 197. The carriage is slotted adjacent the pins, and in these slots are positioned arms 198 and 199 respectively pivoted on the said pins. The arms are respectively provided with rollers 200 and 201 which are adapted to engage the bottom of the slide 24. The arms are connected by pivoted links 202, and these links in turn are connected by a transverse yoke 203. The yoke 203 is provided with slots or notches in which fit pivot bosses projecting upward from the lever 190. The result is that when the lever 190 is swung upward to release the lock, the arms 198 and 199 are swung in a clockwise direction, thus swinging the rollers 200 and 201 upward so as to lift the slide 24 off from the slide 184 and support it independently. The actual raising of the slide may be but a few thousandths of an inch. For returning the slide 24 rearward as soon as it has been released by the lock and elevated by the rollers, there are provided coil springs 205. Preferably these springs are located in long transverse cylindrical apertures 206 in the slide 24. The springs abut at their rear ends against plugs 207 threaded into the apertures, and at their front ends abut against heads 208 on transverse rods 209. The rods 209 extend through central openings in the plugs 207 and are connected at their rear ends with brackets 210 on the carriage 21. Preferably the heads 208 are in the form of pistons and the forward parts of the apertures 206 constitute cylinders 211 in which the pistons 208 fit and move. Secured to the slide 24 is a casting 212 having a transverse passageway which communicates at its ends with the cylinders 211. Also formed in the casting 212 is a fluid reservoir 214. Leading from the passageway 213 into the reservoir 214 is a restricted aperture 215 which is preferably controlled by an adjustable needle valve 216. Leading from the reservoir 214 back to the passageway 213 is an automatic check valve 217. The cylinders 211 together with the passageway 213 and a part of the reservoir 214 are filled with a suitable fluid, which is preferably a liquid such as oil. It will be seen

that as soon as the slide 21 has been elevated and released from the slide 184, the springs 206 tend to move it rearward. This tendency, however, is resisted by the engagement of the pistons 208 with the liquid in the cylinders. This engagement forces the liquid out of the cylinders into the passageway 213 and thence into the reservoir 214 through the restricted aperture 215. The liquid can pass through this aperture only relatively slowly, and thus the return movement of the slide is made to take place very slowly. When the slide is moved quickly forward at the time of next feeding, the check valve 217 opens to permit the liquid to flow from the reservoir 14 back to the passageway 213 and the cylinders 211. The slow return movement causes the former pin to engage the former gently and with a minimum force, so that there is little or no tendency to bend or deflect the parts. In this way I avoid any excessive or variable deflection or distortion such as would affect the contour of the cutter.

It will be noted that the several cams 130, 182, 193 and 194 are so positioned in relation to each other that the operations which they respectively control take place in the following order. First the two slides 184 and 24 are moved backward in unison, they being still locked together. Then the slide 24 is unlocked from the slide 184 and is at the same time elevated on the rollers 200 and 201. At or about the same time the carriage is moved longitudinally to feed the tool to a new cutting position. Then the slide 184 is permitted to return to its normal position. In the meantime the slide 24 is being moved slowly rearward under the control of the springs 205 and the fluid regulating mechanism. After the completion of the return movement of the slide 24, the rollers 200 and 201 are lowered and the slide is again locked to the slide 184.

It is believed that the general operation of the mechanism will be clear from the foregoing description and that a very brief summary will suffice. A former or guide 26 is selected having the desired contour and when a piece is to be cut or otherwise acted upon it is put in place on the carrier. In the case of a blank for a milling cutter, such as illustrated, the blank is mounted on the centers having been previously grooved and roughed out in any usual or preferred manner. If the blank has helical teeth the gearing 78 is adjusted in accordance with the degree of inclination of the teeth and the gearing 56-57 is adjusted in accordance with the number of teeth. The tool is adjusted transversely and longitudinally into engagement with the blank at the right-hand end thereof. Then the machine is started, the spindle 79 and the operating shaft 131 operating alternately in succession. 130

During the rotative movement of the blank, relieving movements of the tool are effected as described, thus cutting the desired relief on the teeth of the blank. After one complete revolution of the blank the rotative movement of the spindle is stopped and also the relieving movements of the tool. The carriage is then fed longitudinally toward the left, the blank turning slightly in conformity with the helical teeth. Just prior to the longitudinal movement the tool slide is withdrawn, thus withdrawing the tool from the blank and the former pin from the former. After the longitudinal movement, the tool slide is moved slowly in the opposite direction, thus gently returning the former pin to the former which is engaged at a new position. The tool assumes a corresponding position with respect to the blank. After this movement of the tool and former pin the blank is again rotated through one revolution and these movements are repeated alternately in succession until the blank is completely formed. It will be seen that with the step-by-step movements described and with a fine feed the former pin can follow or climb a very sharply inclined portion of the contour of the former, the tool being caused to cut a similarly inclined part of the contour of the cutter.

The method of making milling cutters which is herein disclosed, though not claimed, is set forth in my copending application for methods of making milling cutters, Serial No. 326,875, filed Sept. 27, 1919, as a division of my said application Serial No. 286,524. A cutter made in accordance with the said method is set forth in my copending application for milling cutters, Serial No. 368,928, filed March 26, 1920.

What I claim is:

1. In a mechanical movement, the combination of a movable tool, a screw for moving the tool, two ratchet wheels, differently speeded power connections between the respective ratchet wheels and the screw, and two oscillating ratchets adapted respectively to engage the ratchet wheels, whereby the tool may be moved intermittently through either of two distances.

2. In a mechanical movement, the combination of a movable tool, a screw for moving the tool, two ratchet wheels, differently speeded power connections between the respective ratchet wheels and the screw, an oscillating ratchet arm, and two ratchets both carried by the said arm and adapted respectively to engage the ratchet wheels, whereby the tool may be moved intermittently through either of two distances.

3. In a mechanical movement, the combination of a movable tool, a screw for moving the tool, two ratchet wheels, differently speeded power connections between the respective ratchet wheels and the screw, an

oscillating ratchet arm, two ratchets both carried by the said arm and adapted respectively to engage the ratchet wheels, whereby the tool may be moved intermittently through either of two distances, and means for adjusting the amount of movement of the arm to change the said distances of intermittent movement.

4. The combination of a former having a contour differing from a straight line, a former pin adapted to engage the former, and automatic means for effecting at intervals relative movements between the pin and the former to successive fixed relative engaging positions.

5. The combination of a guide, a pin adapted to engage the guide, two supports to which the guide and the pin respectively are normally fixedly secured and whereby their relative movements are limited to two directions at an angle to each other, and automatic means for effecting relative intermittent movements between the supports in one of the said directions.

6. The combination of a tool, a holder, a guide, a pin adapted to engage the guide, and automatic means for effecting at intervals relative movements between the tool and holder and between the pin and guide to successive relatively fixed positions, which positions are determined in part by the engagement of the pin with the guide.

7. The combination of a former having a contour differing from a straight line, a pin adapted to engage the former, two supports to which the former and pin respectively are normally fixedly secured and whereby their relative movements are limited to two directions at an angle to each other, a tool carried by one of the supports, and automatic means for effecting relative intermittent movements between the supports in one of the said directions.

8. The combination of a former having a contour differing from a straight line, a former pin adapted to engage the former, a tool, automatic means for intermittently moving the pin and tool in unison to successive fixed positions, which positions are determined in part by the engagement of the pin with the former, and means for changing the position of the tool with respect to that of the pin.

9. A mechanical movement comprising in combination, a tool, a holder, means for effecting relative movement between the tool and the holder along a predetermined path differing from a straight line, and automatic means for effecting at intervals relative perpendicular withdrawal between the tool and the holder away from the said path.

10. A mechanical movement comprising in combination, a tool, a holder, means for moving the tool with respect to the holder

along a predetermined path differing from a straight line, and automatic means for effecting at intervals relative perpendicular withdrawal between the tool and the holder 5 away from the said path.

11. A mechanical movement comprising in combination, a tool, means for moving the tool along a predetermined path differing from a straight line, and automatic means 10 for perpendicularly withdrawing the tool from the said path at intervals.

12. A mechanical movement comprising in combination, a guide, a pin adapted to engage the guide, means for effecting relative 15 movement between the pin and the guide in a direction generally longitudinal of the latter, and automatic means for separating the pin and the guide at intervals.

13. A mechanical movement comprising in 20 combination, a guide, a pin adapted to engage the guide, two supports to which the guide and the pin respectively are normally fixedly secured and whereby their relative movements are limited to two directions at 25 an angle to each other, means for effecting relative movement between the supports in one of the said directions, and automatic means for effecting relative withdrawal of one support with respect to the other at 30 intervals.

14. A mechanical movement comprising in combination, a former having a contour differing from a straight line, a pin adapted to engage the former, means for effecting 35 relative movement between the pin and the former in a direction generally longitudinal of the latter, and automatic means for separating the pin and the former at intervals.

15. A mechanical movement comprising in 40 combination, a former having a contour differing from a straight line, a pin adapted to engage the former, means for moving the pin along the former, and automatic means for separating the pin and the former at 45 intervals.

16. A mechanical movement comprising in combination, a former having a contour differing from a straight line, a pin adapted to engage the former, means for effecting 50 relative movement between the pin and the former in a direction generally longitudinal of the latter, and automatic means for withdrawing the pin from the former at intervals.

55 17. A mechanical movement comprising in combination, a former having a contour differing from a straight line, a pin adapted to engage the former, means for moving the pin along the former, and automatic 60 means for withdrawing the pin from the former at intervals.

18. A mechanical movement comprising in combination, a tool, a holder, a guide, a pin adapted to engage the guide, means 65 for effecting relative movement between the

tool and holder and between the pin and guide along a path determined by the engagement of the pin with the guide, and automatic means for separating the tool and holder and for separating the pin and the 70 guide at intervals.

19. A mechanical movement comprising in combination, a guide, a pin adapted to engage the guide, two supports to which the guide and pin respectively are normally 75 fixedly secured and whereby their relative movements are limited to two directions at an angle to each other, a tool carried by one of the supports, means for effecting relative movement between the supports in one of 80 the said directions, and automatic means for effecting relative withdrawal of one support with respect to the other at intervals.

20. A mechanical movement comprising in combination, a tool, a holder, a former 85 having a contour differing from a straight line, a pin adapted to engage the former, means for effecting relative movement between the tool and the holder and between the pin and the former along a path determined by the engagement of the pin with the former, and automatic means for effecting a relative withdrawal between the tool and the holder and between the pin and the former at 90 intervals.

21. A mechanical movement comprising in combination, a tool, a holder, a former having a contour differing from a straight line, a pin adapted to engage the former, means for intermittently moving the tool 100 and pin along a path determined by the engagement of the pin with the former, and automatic means for effecting a relative withdrawal between the tool and the holder and between the pin and the former at 105 intervals.

22. A mechanical movement comprising in combination, a tool, a holder, a former having a contour differing from a straight line, a pin adapted to engage the former, 110 means for effecting relative movement between the tool and the holder and between the pin and the former along a path determined by the engagement of the pin with the former, and automatic means for withdrawing the pin from the former and for correspondingly withdrawing the tool at 115 intervals.

23. A mechanical movement comprising in combination, a tool, a former having a 120 contour differing from a straight line, a pin adapted to engage the former, means for moving the tool and pin along a path determined by the engagement of the pin with the former, and automatic means for withdrawing the pin from the former and for correspondingly withdrawing the tool at 125 intervals.

24. A mechanical movement comprising in combination, a tool, a former having a 130

- contour differing from a straight line, a pin adapted to engage the former, means for moving the tool and pin along a path determined by the engagement of the pin
 5 with the former, automatic means for withdrawing the pin from the former and for correspondingly withdrawing the tool at intervals, and means for changing the position of the tool with respect to that of the pin. 70
- 10 25. In a mechanical movement, the combination of a tool, a holder, automatic means for effecting at intervals relative bodily movements between the tool and the holder to successive relatively fixed positions along
 15 a predetermined path, and means for effecting relative withdrawal between the tool and the holder away from the said path at the time of each movement. 80
- 20 26. In a mechanical movement, the combination of a tool, a holder, automatic means for effecting at intervals relative bodily movements between the tool and the holder to successive relatively fixed positions along a predetermined path, the projections of
 25 said positions on a straight line extending in a predetermined direction being uniformly spaced, and means for effecting relative withdrawal between the tool and the holder away from the said path at the time of each movement. 85
- 30 27. In a mechanical movement, the combination of a tool, a holder, automatic means for intermittently moving the tool to successive fixed positions along a predetermined path, and means for effecting relative withdrawal between the tool and the holder away from the said path at the time of each movement. 90
- 35 28. In a mechanical movement, the combination of a tool, a holder, automatic means for intermittently moving the tool to successive fixed positions along a predetermined path, the projections of said positions on a straight line extending in a predetermined direction being uniformly spaced, and means for effecting relative withdrawal between the tool and the holder away from the said path at the time of each movement. 95
- 40 29. In a mechanical movement, the combination of a tool, a holder, automatic means for effecting at intervals relative bodily movements between the tool and the holder to successive relatively fixed positions along
 45 a predetermined path, and means for withdrawing the tool away from the said path at the time of each movement. 100
- 50 30. In a mechanical movement, the combination of a tool, a holder, automatic means for intermittently moving the tool to successive fixed positions along a predetermined path, and means for withdrawing the tool away from the said path at the time of each movement. 105
- 55 31. A mechanical movement comprising
 in combination, a tool, a holder, automatic means for effecting at intervals relative movements between the tool and the holder to successive relatively fixed positions along a predetermined path differing from a straight line, and means for effecting relative withdrawal between the tool and the holder away from the said path at the time of each movement. 110
- 60 32. A mechanical movement comprising in combination, a tool, a holder, automatic means for intermittently moving the tool to successive fixed positions along a predetermined path differing from a straight line, and means for effecting relative withdrawal between the tool and the holder away from the said path at the time of each movement. 115
- 65 33. A mechanical movement comprising in combination, a tool, automatic means for intermittently moving the tool to successive fixed positions along a predetermined path differing from a straight line, and means for withdrawing the tool away from the said path at the time of each movement. 120
- 70 34. A mechanical movement comprising in combination, a guide, a pin adapted to engage the guide, automatic means for effecting at intervals relative movements between the pin and the guide to successive relative engaging positions, and means for separating the pin and the guide at the time of each movement. 125
- 75 35. A mechanical movement comprising in combination, a guide, a pin adapted to engage the guide, two supports to which the guide and the pin respectively are normally fixedly secured and whereby their relative movements are limited to two directions at an angle to each other, automatic means for effecting relative intermittent movements between the supports in one of the said directions, and means for effecting relative withdrawal of one support with respect to the other at the time of each intermittent movement. 130
- 80 36. A mechanical movement comprising in combination, a former having a contour differing from a straight line, a pin adapted to engage the former, automatic means for effecting at intervals relative movements between the pin and the former to successive relative engaging positions, and means for separating the pin and the former at the time of each movement. 135
- 85 37. A mechanical movement comprising in combination, a former having a contour differing from a straight line, a pin adapted to engage the former, automatic means for intermittently moving the pin to successive fixed positions along the former, and means for separating the pin and the former at the time of each movement. 140
- 90 38. A mechanical movement comprising in combination, a former having a contour differing from a straight line, a pin adapted

to engage the former, automatic means for effecting at intervals relative movements between the pin and the former to successive relative engaging positions, and means for 5 withdrawing the pin from the former at the time of each movement.

39. A mechanical movement comprising in combination, a former having a contour differing from a straight line, a pin adapted 10 to engage the former, automatic means for intermittently moving the pin to successive fixed positions along the former, and means for withdrawing the pin from the former at the time of each movement.

15 40. A mechanical movement comprising in combination, a tool, a holder, a guide, a pin adapted to engage the guide, automatic means for effecting at intervals relative movements between the tool and holder and 20 between the pin and guide to successive relatively fixed positions, which positions are determined in part by the engagement of the pin with the guide, and means for separating the tool and holder and for separating 25 the pin and the guide at the time of each movement.

41. A mechanical movement comprising in combination, a guide, a pin adapted to engage the guide, two supports to which 30 the guide and pin respectively are normally fixedly secured and whereby their relative movements are limited to two directions at an angle to each other, a tool carried by one of the supports, automatic means for effecting 35 relative intermittent movements between the supports in one of the said directions, and means for effecting relative withdrawal of one support with respect to the other at the time of each intermittent movement.

40 42. A mechanical movement comprising in combination, a tool, a holder, a former having a contour differing from a straight line, a pin adapted to engage the former, 45 automatic means for effecting at intervals relative movements between the tool and the holder and between the pin and the former to successive positions which are determined in part by the engagement of the pin with 50 the former, and means for effecting a relative withdrawal between the tool and the holder and between the pin and the former at the time of each movement.

43. A mechanical movement comprising 55 in combination, a tool, a holder, a former having a contour differing from a straight line, a pin adapted to engage the former, automatic means for intermittently moving the tool and pin to successive fixed positions which are determined in part by the engagement of the pin with 60 the former, and means for effecting a relative withdrawal between the tool and the holder and between the pin and the former at the time of each movement.

44. A mechanical movement comprising in combination, a tool, a holder, a former having a contour differing from a straight line, a pin adapted to engage the former, 70 automatic means for effecting at intervals relative movements between the tool and the holder and between the pin and the former to successive positions which are determined in part by the engagement of the pin with the former, and means for withdrawing the pin from the former and for correspondingly withdrawing the tool at the time of each movement.

75 45. A mechanical movement comprising in combination, a tool, a former having a contour differing from a straight line, a pin adapted to engage the former, automatic means for intermittently moving the tool and pin to successive fixed positions, means for withdrawing the pin from the former 80 and for correspondingly withdrawing the tool at the time of each movement, and means for changing the position of the tool 85 with respect to that of the pin.

46. A mechanical movement comprising 90 in combination, a tool, a former having a contour differing from a straight line, a pin adapted to engage the former, automatic means for intermittently moving the tool and pin to successive fixed positions, means 95 for withdrawing the pin from the former and for correspondingly withdrawing the tool at the time of each movement, and automatically acting mechanism for regularly moving the tool relatively to the pin in a direction at an angle to the direction of the 100 intermittent movements.

47. The combination of a tool movable to or from an operative position, means for moving the tool toward its operative position, and means supplemental to the last said means for retarding the said movement of the tool.

48. The combination of a tool movable to or from an operative position, means for moving the tool toward its operative position, and fluid controlled means supplemental to the last said means for retarding the said movement of the tool.

49. The combination of a tool movable to 115 or from an operative position, means for moving the tool toward its operative position, and means for retarding the said movement of the tool including a cylinder and a piston therein, the said cylinder having 120 valved apertures associated therewith and permitting the rapid flow of fluid when the tool is moved away from the said position and restricting the flow of fluid when the tool is moved toward the said position.

50. The combination of a tool movable to 125 or from an operative position, means for moving the tool toward its operative position, means for retarding the said movement of the tool including a cylinder and a piston 130

therein, and a fluid reservoir associated with the cylinder, two valved apertures being provided between the cylinder and the reservoir to permit the rapid flow of fluid when the tool is moved away from the said position and to restrict the flow of fluid when the tool is moved toward the said position.

51. The combination of a tool movable to or from an operative position, means for 10 moving the tool toward its operative position, means for retarding the said movement of the tool including two cylinders and two pistons in the respective cylinders, and a fluid reservoir associated with the cylinders, 15 two valved apertures being provided between the two cylinders and the reservoir to permit the rapid flow of fluid when the tool is moved away from the said position and to restrict the flow of fluid when the tool is 20 moved toward the said position.

52. The combination of a tool movable to or from an operative position, means for retarding the movement of the tool toward the said position including a cylinder and a piston 25 ton therein, a piston rod connecting the piston with the tool, and a spring surrounding the rod and serving to move the tool toward the said position.

53. The combination of a tool movable to 30 or from an operative position, means for retarding the movement of the tool toward the said position including two cylinders and two pistons in the respective cylinders, piston rods connecting the respective pistons 35 with the tool, and springs surrounding the respective rods and serving to move the tool toward the said position.

54. The combination of a movable slide, a guideway for the slide, and means for vertically separating the slide and guideway by a relative movement thereof.

55. The combination of a movable slide, a guideway for the slide, and means for vertically moving the slide out of contact with 45 the guideway.

56. The combination of a movable slide, a guideway for the slide, and rollers adapted to engage the slide to move it vertically out of contact with the guideway.

50 57. The combination of a movable slide, a guideway for the slide, rollers adapted to engage the slide to elevate it out of contact with the guideway, and parallel motion links controlling the rollers.

55 58. The combination of a movable slide, a guideway for the slide, means for moving the slide, means supplemental to the last said means for retarding the said movement of the slide, and means for vertically separating 60 the slide and guideway.

59. The combination of a tool movable to or from a fixed operative position, automatic means for rapidly withdrawing the tool from the said position, and automatic 65 means for slowly returning the tool toward

the said position after each withdrawal.

60. The combination of a tool movable to or from an operative position, automatic means for withdrawing the tool from the said position, and means supplemental to 70 the last said means and acting independently thereof for returning the tool toward the said position after each withdrawal.

61. The combination of a tool movable to or from an operative position, automatic 75 means for withdrawing the tool from the said position, means for returning the tool toward the said position after each withdrawal, and means supplemental to the withdrawing means for retarding the movement 80 of the tool toward the said position.

62. The combination of a tool movable to or from an operative position, automatic means for withdrawing the tool from the said position, means for returning the tool 85 toward the said position after each withdrawal, and means supplemental to the withdrawing means and acting independently thereof for retarding the movement of the tool toward the said position.

90 63. The combination of a movable slide, a guideway for the slide, automatic means for moving the slide from a predetermined position, means for returning the slide to the said position after each withdrawal, and 95 means associated with the withdrawing means for vertically separating the slide and guideway.

64. The combination of a movable slide, a guideway for the slide, automatic means for 100 moving the slide from a predetermined position, means associated with the withdrawing means for vertically separating the slide and guideway, and means supplemental to the withdrawing means and acting independently 105 thereof for returning the slide to the said position after each withdrawal.

65. In a mechanical movement of the class described, the combination of a holder, a tool, automatic mechanism for effecting at 110 intervals relative movements between the tool and the holder longitudinally of the latter, automatic mechanism for rapidly withdrawing the tool from the holder before each longitudinal movement, and automatic mechanism for slowly returning the tool to the holder after each longitudinal movement.

115 66. In a mechanical movement of the class described, the combination of a tool, automatic mechanism for moving the tool at intervals in a predetermined direction, automatic mechanism for rapidly withdrawing the tool transversely of the said direction before each movement, and automatic mechanism for slowly returning the tool transversely of the said direction after each movement.

120 67. In a mechanical movement of the class described, the combination of a holder, a tool, automatic mechanism for effecting at 125

- intervals relative movements between the tool and the holder longitudinally of the latter, automatic mechanism for withdrawing the tool from the holder before each longitudinal movement, and automatic mechanism 5 acting entirely independently of the last said mechanism for returning the tool toward the holder after each longitudinal movement.
- 10 68. In a mechanical movement of the class described, the combination of a tool, automatic mechanism for moving the tool at intervals in a predetermined direction, automatic mechanism for withdrawing the tool 15 transversely of the said direction before each movement, and automatic mechanism acting entirely independently of the last said mechanism for returning the tool transversely of the said direction after each movement.
- 20 69. In a mechanical movement of the class described, the combination of a holder, a tool, automatic mechanism for effecting at intervals relative movements between the tool and the holder longitudinally of the 25 latter, mechanism for withdrawing the tool from the holder at the time of each longitudinal movement, means for returning the tool toward the blank after each withdrawal, and means supplemental to the withdrawal and returning means for retarding the 30 movement of the tool toward the holder.
70. A mechanical movement comprising in combination, a holder, and a tool relatively movable in a predetermined direction, 35 the said tool being also movable transversely of the said direction, means for effecting relative movement between the tool and the holder in the said direction, automatic means for rapidly withdrawing the tool 40 transversely of the said direction at intervals, automatic means for slowly returning the tool transversely of the said direction after each withdrawal, and means for differently limiting the returning movements of 45 the tool so that the successive positions of the tool lie in a path in a direction different from the said predetermined direction.
71. A mechanical movement comprising in combination, a tool movable in a predetermined direction and also movable transversely of the said direction, means for moving the tool in the said direction, automatic means for rapidly withdrawing the tool 50 transversely of the said direction at intervals, automatic means for slowly returning the tool transversely of the said direction after each withdrawal, and means for differently limiting the returning movements of the tool so that the successive positions of the tool lie in a path in a direction different from the said predetermined direction.
- 55 72. A mechanical movement comprising in combination, a holder and a tool relatively movable in the predetermined direction, the said tool being also movable transversely of the said direction, means for effecting relative movement between the tool and the holder in the said direction, automatic means for rapidly withdrawing the tool transversely of the said direction at intervals, automatic means for slowly returning the tool transversely of the said direction after each withdrawal, and means for differently limiting the returning movements of the tool so that the successive positions of the tool lie in a path in a direction different from the said predetermined direction.
- 60 73. A mechanical movement comprising in combination, a holder and a tool relatively movable in a predetermined direction, the said tool being also movable transversely of the said direction, means for effecting relative movement between the tool and the holder in the said direction, automatic means for rapidly withdrawing the tool transversely of the said direction at intervals, automatic means for slowly returning the tool transversely of the said direction after each withdrawal, and means for differently limiting the returning movements of the tool so that the successive positions of the tool lie in a path in a direction different from the said predetermined direction.
- 65 74. A mechanical movement comprising in combination, a tool movable in a predetermined direction and also movable transversely of the said direction, means for moving the tool in the said direction, automatic means for withdrawing the tool transversely of the said direction at intervals, automatic means for returning the tool transversely of the said direction after each withdrawal, and means supplemental to the withdrawing means and acting independently thereof for retarding the said returning movements and means for differently limiting the returning movements of the tool so that the successive positions of the tool lie in a path in a direction different from the said predetermined direction.
75. A mechanical movement comprising in combination, a former and a former pin relatively movable in a predetermined direction, means for effecting relative movement between the pin and the former in the said direction, automatic means for rapidly separating the pin and the former at intervals, and automatic means for slowly causing the engagement of the pin and the former after each separation.
- 80 76. A mechanical movement comprising in combination, a former and a former pin relatively movable in a predetermined direction, means for effecting relative movement between the pin and the former in the said direction, automatic means for separating the pin and the former at intervals, and automatic means for slowly causing the engagement of the pin and the former after each separation.

ing the pin and the former at intervals, and automatic means supplemental to the separating means and acting independently thereof for causing the engagement of the pin and the former after each separation.

77. A mechanical movement comprising in combination, a former and a former pin relatively movable in a predetermined direction, means for effecting relative movement between the pin and the former in the said direction, automatic means for separating the pin and the former at intervals, automatic means for causing the engagement of the pin and the former after each separation.

10 78. A mechanical movement comprising in combination, a former and a former pin relatively movable in a predetermined direction, means for effecting relative movement between the pin and the former in the said direction, automatic means for separating the pin and the former at intervals,

15 automatic means for causing the engagement of the pin and the former after each separation, and means supplemental to the said separating means for retarding the said engagement.

79. A mechanical movement comprising in combination, a former and a former pin relatively movable in a predetermined direction, means for effecting relative movement between the pin and the former in the said direction, automatic means for separating the pin and the former at intervals, 20 automatic means for causing the engagement of the pin and the former after each separation, and fluid controlled means for retarding the said engagement.

80. A mechanical movement comprising in combination, a holder and a tool relatively movable in a predetermined direction, means including a former and a former pin for controlling the relative positions of the tool and holder, means for effecting relative movement between the tool and holder and between the pin and the former in the said predetermined direction, automatic means for rapidly separating the pin and the former at intervals, and automatic means 25 for slowly causing the engagement of the pin and the former after each separation.

81. A mechanical movement comprising in combination, a holder and a tool relatively movable in a predetermined direction, means including a former and a former pin for controlling the relative positions of the tool and holder, means for effecting relative movement between the tool and holder and between the pin and the former in the said 30 predetermined direction, automatic means for rapidly effecting relative withdrawal between the tool and holder and between the pin and former at intervals, and automatic means for slowly effecting a relative

35 return movement between the tool and holder and between the pin and former after each withdrawal.

82. A mechanical movement comprising in combination, a holder and a tool relatively movable in a predetermined direction, means including a former and a former pin for controlling the relative positions of the tool and holder, means for effecting relative movement between the tool and holder and between the pin and the former

in the said predetermined direction, automatic means for effecting relative withdrawal between the tool and holder and between the pin and former at intervals, and automatic means supplemental to the withdrawing means and acting independently thereof for effecting a relative return movement between the tool and holder and between the pin and former after each withdrawal.

83. A mechanical movement comprising in combination, a holder and a tool relatively movable in a predetermined direction, means including a former and a former pin for controlling the relative positions of the tool and holder, means for effecting relative movement between the tool and holder and between the pin and the former in the said predetermined direction, automatic means for effecting relative withdrawal between the tool and holder and between the pin and former at intervals, automatic means for effecting a relative return movement between the tool and holder and between the pin and former after each withdrawal, and means supplemental to the said withdrawing means for retarding the said return movement.

84. In a mechanical movement, the combination of a holder and a tool relatively movable in a predetermined direction, the said tool being also movable transversely of the said direction, means for effecting at intervals relative movements between the tool and the holder in the said direction to successive fixed relative positions, automatic means for rapidly withdrawing the tool transversely of the said direction before each movement, automatic means for slowly returning the tool transversely of the said direction after each withdrawal, and means for differently limiting the returning movements of the tool so that the successive positions of the tool lie in a path in a direction different from the said predetermined direction.

85. In a mechanical movement, the combination of a tool movable in a predetermined

- direction and also movable transversely of the said direction, means for intermittently moving the tool in the said direction, automatic means for rapidly withdrawing the tool transversely of the said direction before each intermittent movement, automatic means for slowly returning the tool transversely of the said direction after each withdrawal, and means for differently limiting the returning movements of the tool so that the successive positions of the tool lie in a path in a direction different from the said predetermined direction.
86. In a mechanical movement, the combination of a holder and a tool relatively movable in a predetermined direction, the said tool being also movable transversely of the said direction, means for effecting at intervals relative movements between the tool and the holder in the said direction to successive fixed relative positions, automatic means for rapidly withdrawing the tool transversely of the said direction before each movement, automatic means for slowly returning the tool transversely of the said direction after each withdrawal, and means for differently limiting the returning movements of the tool so that the successive positions of the tool lie in a path differing from a straight line.
87. In a mechanical movement, the combination of a holder and a tool relatively movable in a predetermined direction, the said tool being also movable transversely of the said direction, means for effecting at intervals relative movements between the tool and the holder in the said direction to successive fixed relative positions, automatic means for rapidly withdrawing the tool transversely of the said direction before each movement, automatic means for returning the tool transversely of the said direction after each withdrawal, means supplemental to the withdrawing means and acting independently thereof for retarding the said returning movements, and means for differently limiting the returning movements of the tool so that the successive positions of the tool lie in a path in a direction different from the said predetermined direction.
88. In a mechanical movement, the combination of a tool movable in a predetermined direction and also movable transversely of the said direction, means for intermittently moving the tool in the said direction, automatic means for withdrawing the tool transversely of the said direction before each longitudinal movement, automatic means for returning the tool transversely of the said direction after each withdrawal, means supplemental to the withdrawing means and acting independently thereof for retarding the said returning movements, and means for differently limiting the last said movements of the tool so that the successive posi-
- tions of the tool lie in a path in a direction different from the said predetermined direction.
89. In a mechanical movement, the combination of a former and a former pin relatively movable in a predetermined direction, means for effecting at intervals relative movements between the pin and the former in the said direction to successive fixed relative positions, automatic means for rapidly separating the pin and the former before each movement, and automatic means for slowly causing the engagement of the pin and the former after each separation.
90. In a mechanical movement, the combination of a former and a former pin relatively movable in a predetermined direction, means for effecting at intervals relative movements between the pin and the former in the said direction to successive fixed relative positions, automatic means for separating the pin and the former before each movement, and automatic means supplemental to the separating means and acting independently thereof for causing the engagement of the pin and the former after each separation.
91. In a mechanical movement, the combination of a former and a former pin relatively movable in a predetermined direction, means for effecting at intervals relative movements between the pin and the former in the said direction to successive fixed relative positions, automatic means for separating the pin and the former before each movement, automatic means for causing the engagement of the pin and the former after each separation, and means supplemental to the said separating means for retarding the said engagement.
92. In a mechanical movement, the combination of a holder and a tool relatively movable in a predetermined direction, means including a former and a former pin for controlling the relative positions of the tool and holder, means for effecting at intervals relative movements between the tool and holder and between the pin and the former in the said predetermined direction to successive fixed relative positions, automatic means for rapidly separating the pin and the former before each movement, and automatic means for slowly causing the engagement of the pin and the former after each separation.
93. In a mechanical movement, the combination of a holder and a tool relatively movable in a predetermined direction, means including a former and a former pin for controlling the relative positions of the tool and holder, means for effecting at intervals relative movements between the tool and holder and between the pin and the former in the said predetermined direction to successive fixed relative positions,

automatic means for rapidly effecting relative withdrawal between the tool and holder and between the pin and former before each movement, and automatic means for slowly effecting a relative return movement between the tool and holder and between the pin and former after each withdrawal.

94. In a mechanical movement, the combination of a holder and a tool relatively movable in a predetermined direction, means including a former and a former pin for controlling the relative positions of the holder and tool, means for effecting at intervals relative movements between the tool and holder and between the pin and the former in the said predetermined direction to successive fixed relative positions, automatic means for effecting relative withdrawal between the tool and holder and between the pin and former before each movement, and automatic means supplemental to the withdrawing means and acting independently thereof for effecting a relative return movement between the tool and holder and between the pin and former after each withdrawal.

95. In a mechanical movement, the combination of a holder and a tool relatively movable in a predetermined direction, means including a former and a former pin for controlling the relative positions of the holder and tool, means for effecting at intervals relative movement between the tool and holder and between the pin and the former in the said predetermined direction to successive fixed relative positions, automatic means for effecting relative withdrawal between the tool and holder and between the pin and former before each movement, automatic means for effecting a relative return movement between the tool and holder and between the pin and former after each withdrawal, and means supplemental to the said withdrawing means for retarding the said return movement.

96. The described combination of a movable tool, a support for the tool, and automatic means for locking the tool to the support at intervals and for releasing it at intervals to permit movement.

97. The described combination of a movable slide, a support for the slide, and automatic means for locking the slide to the support at intervals and for releasing it at intervals to permit movement.

98. The described combination of a movable slide, a support for the slide, means for locking the slide to the support or for releasing it to permit transverse movement and means for elevating the slide out of contact with the support when it is released.

99. The described combination of a movable slide, a support for the slide, means for locking the slide to the support or for releasing it to permit movement, and means

including anti-friction rollers for elevating the slide out of contact with the support when it is released.

100. The described combination of a movable slide, a support for the slide, automatic means for locking the slide to the support at intervals and for releasing it at intervals to permit movement, and automatic means for elevating the slide out of contact with the support each time it is released.

101. The described combination of a movable carriage, a relatively movable tool on the carriage, automatic means for moving the tool relatively to the carriage at intervals, locking means between the tool and the carriage, and automatic means for effecting unlocking at the time of each relative movement and for subsequently effecting locking.

102. The described combination of a movable carriage, a relatively movable slide on the carriage, automatic means for moving the slide relatively to the carriage at intervals, locking means between the slide and the carriage, and automatic means for effecting unlocking at the time of each relative movement and for subsequently effecting locking.

103. The described combination of a movable carriage, a relatively movable slide on the carriage, automatic means for moving the slide relatively to the carriage at intervals, locking means between the slide and the carriage, automatic means for effecting unlocking at the time of each withdrawal and for subsequently effecting locking, and automatic means for elevating the slide each time it is unlocked.

104. The described combination of a movable slide having a slot therein extending in the direction of movement of the slide, a second movable slide supporting the first slide, and means carried by the second slide and extending through the slot for locking the slides together or for releasing them to permit relative movement.

105. The described combination of a movable slide having a slot therein extending in the direction of movement of the slide, a second movable slide supporting the first slide and having an aperture registering with the slot, and means including a vertically movable stud extending through the slot and the aperture for locking the slides together or for releasing them to permit relative movement.

106. The described combination of a movable slide, a second movable slide supporting the first slide, and automatic means for locking the slides together at intervals and for releasing them at intervals to permit relative movement.

107. The described combination of a movable slide, a second movable slide support-

ing the first slide, means for locking the slides together or for releasing them to permit relative movement, and automatic means for elevating the first slide out of contact with the second slide when it is released.

108. The described combination of a movable slide, a second movable slide supporting the first slide, automatic means for locking the slides together at intervals to permit relative movement, and automatic means for elevating the first slide out of contact with the second slide when it is released.

109. The described combination of a movable carriage, a relatively movable slide on the carriage, a second slide mounted on the first said slide and movable thereon, automatic means for moving the second slide relatively to the carriage at intervals, locking means between the slides, and automatic means for effecting unlocking at the time of each withdrawal and for subsequently effecting locking.

110. The described combination of a movable carriage, a relatively movable slide on the carriage, a second slide mounted on the first said slide and movable thereon, automatic means for moving the second slide relatively at intervals, locking means between the slides, automatic means for effecting unlocking at the time of each said movement of the second slide and for subsequently effecting locking, and automatic means for elevating the second slide out of contact with the first slide each time unlocking takes place.

111. The described combination of a movable carriage, a relatively movable slide on the carriage, a second slide mounted on the first said slide and movable thereon, locking means between the slides, automatic means engaging the first said slide for moving both slides relatively to the carriage at intervals, and automatic means acting immediately after each said movement of the slides to unlock the second slide from the first slide and subsequently acting to lock the second slide to the first slide.

112. In a mechanical movement, the combination of a movable carriage, a relatively movable tool on the carriage, automatic means for moving the carriage at intervals, locking means between the tool and the carriage, and automatic means for effecting locking after each carriage movement and unlocking before the next following carriage movement.

113. In a mechanical movement, the combination of a movable carriage, a relatively movable slide on the carriage, automatic means for moving the carriage at intervals, locking means between the slide and the carriage, and automatic means for effecting locking after each carriage movement and unlocking before the next following carriage movement.

114. In a mechanical movement, the combination of a movable carriage, a relatively movable slide on the carriage, automatic means for moving the carriage at intervals, locking means between the slide and the carriage, automatic means for effecting locking after each carriage movement and unlocking before the next following carriage movement and automatic means for elevating the slide each time it is unlocked. 70

115. In a mechanical movement, the combination of a movable carriage, a relatively movable tool on the carriage, automatic means for moving the carriage at intervals, automatic means for moving the tool relatively to the carriage at the time of each carriage movement, locking means between the tool and the carriage, and automatic means for effecting locking after each carriage movement and unlocking before the 85 next following carriage movement. 75

116. In a mechanical movement, the combination of a movable carriage, a relatively movable tool on the carriage, automatic means for moving the carriage at intervals, 90 automatic means for moving the tool relatively to the carriage at the time of each carriage movement, means for returning the tool relatively to the carriage in the opposite direction after each carriage movement, 95 locking means between the tool and the carriage, and automatic means for effecting unlocking before each withdrawal and locking after each return movement.

117. In a mechanical movement, the combination of a movable carriage, a relatively movable slide on the carriage, automatic means for moving the carriage longitudinally at intervals, automatic means for moving the slide relatively to the carriage at the time of each carriage movement, locking means between the slide and the carriage, and automatic means for effecting locking after each carriage movement and unlocking before the next following carriage movement. 100 105

118. In a mechanical movement, the combination of a movable carriage, a relatively movable slide on the carriage, automatic means for moving the carriage at intervals, automatic means for moving the slide relatively to the carriage at the time of each carriage movement, locking means between the slide and the carriage, automatic means for effecting locking after each carriage movement and unlocking before the next 120 following carriage movement, and automatic means for elevating the slide each time it is unlocked. 110 115

119. In a mechanical movement, the combination of a movable carriage, a relatively movable slide on the carriage, automatic means for moving the slide relatively to the carriage at the time of each carriage movement, locking means between the slide and the carriage, and automatic means for effect- 125 130

ing locking after each carriage movement and unlocking before the next following carriage movement.

120. In a mechanical movement, the combination of a movable carriage, a relatively movable slide on the carriage, automatic means for moving the slide relatively to the carriage at the time of each carriage movement, means for returning the slide relatively to the carriage after each carriage movement, locking means between the slide and the carriage, and automatic means for effecting unlocking before each withdrawal and locking after each return movement.

121. In a mechanical movement, the combination of a movable carriage, a relatively movable slide on the carriage, a second slide mounted on the first said slide and relatively movable thereon, automatic means for moving the carriage at intervals, automatic means for moving the second slide relatively to the carriage at the time of each longitudinal movement, locking means between the slides, and automatic means for effecting unlocking at the time of each carriage movement and withdrawal and for subsequently effecting locking.

122. In a mechanical movement, the combination of a movable carriage, a relatively movable slide on the carriage, a second slide mounted on the first said slide and relatively movable thereon, automatic means for moving the carriage at intervals, automatic means for moving the second slide relatively to the carriage at the time of each longitudinal movement, locking means between the slides, automatic means for effecting unlocking at the time of each carriage movement and relative slide movement and for subsequently effecting locking, and automatic means for elevating the second slide out of contact with the first said slide each time unlocking takes place.

123. In a mechanical movement, the combination of a movable carriage, a relatively movable slide on the carriage, a second slide mounted on the first said slide and relatively movable thereon, automatic means for moving the carriage at intervals, locking means between the slides, automatic means engaging the first said slide for moving both slides relatively to the carriage at the time of each carriage movement, and automatic means acting immediately after the said movement of the slides to unlock the second slide from the first slide and subsequently acting to lock the second slide to the first slide.

124. The combination in a mechanical movement of the class described, of a movable carriage, a tool on the carriage relatively movable transversely of the direction of carriage movement, automatic means for moving the carriage at intervals, means for controlling the tool so as to cause it to as-

sume different positions with respect to the carriage following successive movements of the carriage locking means between the tool and the carriage and automatic means for effecting locking after each carriage movement and unlocking before the next following carriage movement.

125. The combination in a mechanical movement of the class described, of a movable carriage, a slide on the carriage relatively movable transversely of the direction of carriage movement, automatic means for moving the carriage at intervals, means for controlling the slide to cause it to assume different positions following successive movements of the carriage, locking means between the slide and the carriage, and automatic means for effecting locking after each carriage movement and unlocking before the next following carriage movement.

126. The combination in a mechanical movement of the class described, of a movable carriage, a slide on the carriage relatively movable transversely of the direction of carriage movement, automatic means for moving the carriage at intervals, means including a former and a former pin for controlling the slide to cause it to assume different positions following successive movements of the carriage, locking means between the slide and the carriage, and automatic means for effecting locking after each carriage movement and unlocking before the next following carriage movement.

127. The combination in a mechanical movement of the class described, of a movable carriage, a slide on the carriage relatively movable transversely of the direction of carriage movement, automatic means for moving the carriage at intervals, automatic means for moving the slide transversely at the time of each longitudinal movement, means for controlling the slide to cause it to assume different positions following successive movements of the carriage and of the slide, locking means between the slide and the carriage, and automatic means for effecting locking after each carriage movement and unlocking before the next following carriage movement.

128. The combination in a mechanical movement of the class described, of a movable carriage, automatic means for moving the carriage at intervals, a former, a former pin on the carriage engaging the former and movable transversely of the direction of carriage movement, locking means between the former pin and the carriage, and automatic means for effecting locking after each carriage movement and unlocking before the next following carriage movement.

129. The combination in a mechanical movement of the class described, of a movable carriage, a tool on the carriage rela-

tively movable transversely of the direction of carriage movement, automatic means for moving the carriage at intervals, means including a former and a relatively movable former pin on the carriage for controlling the tool to cause it to assume different positions with respect to the carriage following successive movements of the carriage, locking means between the former pin and the carriage, and automatic means for effecting locking after each carriage movement and unlocking before the next following carriage movement.

130. The combination in a mechanical movement of the class described, of a movable carriage, a tool on the carriage relatively movable transversely of the direction of carriage movement, automatic means for moving the carriage longitudinally at intervals, means including a former and a relatively movable former pin on the carriage for controlling the tool to cause it to assume different positions with respect to the carriage following successive movements of the carriage, automatic means for withdrawing the former pin from the former at the time of each carriage movement, locking means between the former pin and the carriage, and automatic means for effecting locking after each carriage movement and unlocking before the next following carriage movement.

131. The combination in a mechanical movement of the class described, of a movable carriage, a tool on the carriage relatively movable transversely of the direction of carriage movement, automatic means for moving the carriage at intervals, means including a former and a relatively movable former pin on the carriage for controlling the tool to cause it to assume different positions with respect to the carriage following successive movements of the carriage, locking means between the former pin and the carriage and between the tool and the carriage, and automatic means for effecting locking after each carriage movement and unlocking before the next following carriage movement.

132. The combination in a mechanical movement of the class described, of a movable carriage, a tool on the carriage relatively movable transversely of the direction of carriage movement, automatic means for moving the carriage at intervals, means including a former and a relatively movable former pin on the carriage for controlling the tool to cause it to assume different positions with respect to the carriage following successive movements of the carriage, automatic means for withdrawing the former pin from the former at the time of each carriage movement, locking means between the former pin and the carriage and between the tool and the carriage, and automatic

means for effecting locking after each carriage movement and unlocking before the next following carriage movement.

133. The combination in a mechanical movement of the class described, of a movable carriage, a slide on the carriage relatively movable transversely of the direction of carriage movement, a tool on the slide, automatic means for moving the carriage at intervals, means including a former and a former pin on the slide for controlling the slide to cause it to assume different positions following successive movements of the carriage, automatic means for moving the slide to move the tool and withdraw the former pin from the former at the time of each carriage movement, locking means between the slide and the carriage, and automatic means for effecting locking after each carriage movement and unlocking before the next following carriage movement.

134. The combination in a mechanical movement of the class described, of a movable carriage, a movable slide on the carriage relatively movable transversely of the direction of carriage movement, a second slide mounted on the first slide and relatively movable thereon in the said transverse direction, a tool on the second slide, automatic means for moving the carriage at intervals, means including a former and a former pin on the second slide for controlling the said slide to cause it to assume different positions following successive movements of the carriage, automatic means for moving the second slide to move the tool and withdraw the former pin from the former at the time of each carriage movement, locking means between the two slides, and automatic means for effecting locking after each carriage movement and unlocking before the next following carriage movement.

135. The combination in a mechanical movement of the class described, of a movable carriage, a slide on the carriage relatively movable transversely of the direction of carriage movement, a second slide mounted on the first slide and relatively movable thereon in the said transverse direction, a tool on the second slide, automatic means for moving the carriage at intervals, means including a former and former pin on the second slide for controlling the said slide to cause it to assume different positions following successive movements of the carriage, locking means between the two slides, automatic means engaging the first said slide for moving both slides to move the tool and withdraw the pin from the former at the time of each carriage movement, and automatic means acting immediately after withdrawal to unlock the tool slide from the first slide and subsequently acting to lock the tool slide to the first slide.

136. The combination of a tool movable to or from an operative position, means for moving the tool toward its operative position, means supplemental to the last said means for retarding the said movement of the tool, and automatic means for locking the tool in the said position. 5
137. The combination of a tool movable to or from an operative position, means for moving the tool toward its operative position, fluid controlled means supplemental to the last said means for retarding the said movement of the tool, and automatic means for locking the tool in the said position. 10
138. The combination of a movable slide, means for moving the slide to a predetermined position, means supplemental to the last said means for retarding the said movement of the slide, and automatic means for locking the slide in the said position. 15
139. The combination of a movable tool slide, a guideway for the slide, a tool on the slide, means for moving the slide so as to move the tool toward an operative position, means for elevating the slide out of contact with the guideway, means supplemental to the slide moving means for retarding the said movement of the slide, and automatic means for locking the slide with the tool in the said position. 20
140. The combination of a tool movable to or from an operative position, automatic means for rapidly withdrawing the tool from its operative position, means for slowly returning the tool to the said position after each withdrawal, and automatic means for locking the tool in its operative position after return. 25
141. The combination of a tool movable to or from an operative position, automatic means for withdrawing the tool from its operative position, means supplemental to the last said means and acting independently thereof for returning the tool to the said position after each withdrawal, and automatic means for locking the tool in the said position. 30
142. The combination of a tool movable to or from an operative position, automatic means for withdrawing the tool from its operative position, means for returning the tool to the said position after each withdrawal, means for retarding the return movement of the tool, and automatic means for locking the tool in its operative position after return. 35
143. The combination of a tool movable to or from an operative position, automatic means for withdrawing the tool from its operative position, means for returning the tool toward the said position after each withdrawal, means supplemental to the withdrawing means and acting independently thereof for retarding the return movement of the tool, and automatic means for locking the tool in its operative position after return. 40
- the tool in its operative position after return. 144. The combination of a movable slide, automatic means for moving the slide to withdraw it from a predetermined position at intervals, means supplemental to the last said means and acting independently thereof for returning the slide to the said position after each withdrawal, and automatic means for locking the slide in the said position after each withdrawal. 70
145. The combination of a movable slide, a guideway for the slide, automatic means for moving the slide to withdraw it from a predetermined position at intervals, means for elevating the slide out of contact with the guideway, means supplemental to the last said means and acting independently thereof for moving the slide to return the tool toward the said position after each withdrawal, and automatic means for locking the slide with the tool in the said position after return. 80
146. The combination of a movable slide, a second relatively movable slide supporting the first slide, automatic means for moving the second slide to withdraw it from a predetermined position at intervals, means supplemental to the last said means for returning the slide toward the said position after each withdrawal, and automatic means for locking the two slides together or for unlocking them. 90
147. The combination of a movable slide, a second relatively movable slide supporting the first slide, automatic means for moving the first slide to withdraw it from a predetermined position at intervals, means supplemental to the last said means for returning the slide toward the said position after each withdrawal, means for locking the two slides together or for unlocking them, and automatic means for elevating the tool slide out of contact with the other slide each time unlocking takes place. 100
148. The combination of a movable slide, a second movable slide supporting the first slide, automatic means engaging the second slide for moving both slides to withdraw the first slide from a predetermined position at intervals, automatic means acting immediately after withdrawal to unlock the first slide from the other slide and subsequently acting to lock the two slides together, and automatic means supplemental to the withdrawing means and acting immediately after unlocking for moving the first slide relatively to the second slide toward the said position. 110
149. The combination of a movable slide, a second movable slide supporting the first slide, automatic means engaging the second slide for moving both slides to withdraw the first slide from a predetermined position at intervals, automatic means acting immediately after withdrawal to unlock the first 125
150. The combination of a movable slide, a second movable slide supporting the first slide, automatic means engaging the second slide for moving both slides to withdraw the first slide from a predetermined position at intervals, automatic means acting immediately after withdrawal to unlock the first 130

slide from the second slide and subsequently acting to lock the two slides together, automatic means supplemental to the withdrawing means and acting immediately after unlocking for moving the first slide relatively to the second slide to the said position, and means associated with the withdrawing means for returning the second slide to its initial position after the two slides have been unlocked.

150. In combination in a mechanical movement of the class described, a holder, a tool, automatic mechanism for effecting at intervals relative movements between the tool and the holder to successive fixed positions along a predetermined path, mechanism for rapidly withdrawing the tool from the said path before each said movement, mechanism for slowly returning the tool to the said path after each said movement, and means for locking the tool in position after it has been returned.

151. In combination in a mechanical movement of the class described, a holder, a tool, automatic mechanism for effecting at intervals relative movements between the tool and the holder to successive fixed positions along a predetermined path, mechanism for withdrawing the tool from the said path before each said movement, mechanism acting entirely independently of the last said mechanism for returning the tool to the said path after each longitudinal movement, and automatic means for locking the tool in position after it has been returned.

152. In combination in a mechanical movement of the class described, a carrier, a tool, automatic mechanism for effecting at intervals relative movements between the tool and the holder to successive fixed positions along a predetermined path, mechanism for withdrawing the tool from the said path at the time of each said movement, means for returning the tool toward the said path after each withdrawal, means for retarding the movement of the tool toward the said path, and automatic means for locking the tool in position after it has been returned.

153. In combination in a mechanical movement of the class described, a movable carriage, a relatively movable slide on the carriage, automatic means for moving the carriage at intervals, automatic means for relatively moving the slide to withdraw it from a predetermined position at the time of each carriage movement, and mechanism acting entirely independently of the last said mechanism for returning the slide to the said position after each carriage movement.

154. In combination in a mechanical movement of the class described, a movable carriage having a guideway thereon, a movable slide on the said guideway, automatic

means for moving the carriage at intervals, automatic means for relatively moving the slide to withdraw it from a predetermined position at the time of each carriage movement, means for elevating the slide out of contact with the guideway, means supplemental to the last said means and acting independently thereof for returning the slide to the said position after each withdrawal, and automatic means for locking the slide in the said position.

155. In combination in a mechanical movement of the class described, a movable carriage, a movable slide on the carriage, a second movable slide on the carriage supporting the first slide, automatic means for moving the carriage at intervals; automatic means for moving the first slide to withdraw it from a predetermined position at the time of each carriage movement, means supplemental to the last said means for returning the first slide to the said position after each withdrawal, and means for locking the two slides together or for unlocking them.

156. In combination in a mechanical movement of the class described, a movable carriage, a movable slide on the carriage, a second movable slide on the carriage supporting the first slide, automatic means for moving the carriage at intervals, automatic means engaging the second said slide for moving both slides transversely to withdraw the first slide from a predetermined position at the time of each carriage movement, automatic means acting immediately after withdrawal to unlock the first slide from the second slide and subsequently acting to lock the two slides together, and automatic means supplemental to the withdrawing means and acting immediately after unlocking for returning the first slide relatively to the second slide to the said position.

157. In combination in a mechanical movement of the class described, a movable carriage, a movable slide on the carriage, a second movable slide on the carriage supporting the first slide, automatic means for moving the carriage longitudinally at intervals, automatic means engaging the second slide for moving both slides to withdraw the first slide from a predetermined position at the time of each longitudinal movement, automatic means acting immediately after withdrawal to unlock the first slide from the second slide and subsequently acting to lock the two slides together, automatic means supplemental to the withdrawing means and acting immediately after locking for returning the first slide relatively to the second slide to the said position, and means associated with the withdrawing means for returning the second slide to its initial position after the two slides are unlocked.

- vals relative movements between the tool and the holder in the said direction, automatic means for rapidly withdrawing the tool transversely of the said direction at the time 5 of each movement, means for slowly returning the tool after each withdrawal, means for limiting the return movements of the tool at different positions, and means for locking the tool in position after each re-
 10 turning movement.
166. In a mechanical movement of the class described, the combination of a holder and a tool relatively movable in a predetermined direction, the said tool being also 15 movable transversely of the said direction, automatic mechanism for effecting at intervals relative movements between the tool and the holder in the said direction, automatic means for withdrawing the tool transversely 20 of the said direction at the time of each longitudinal movement, means supplemental to the withdrawing means and acting independently thereof for returning the tool after each withdrawal, means for limiting 25 the return movements of the tool at different positions, and means for locking the tool in position after each returning movement.
167. In a mechanical movement of the class described, the combination of a former 30 and a former pin relatively movable longitudinally, means for effecting at intervals relative longitudinal movements between the pin and former, automatic means for rapidly withdrawing the pin from the former at the time of each longitudinal movement, means for slowly returning the pin to the former after each withdrawal, and automatic means for locking the pin in its returned position.
- 35 168. In a mechanical movement of the class described, the combination of a former and a former pin relatively movable longitudinally, means for effecting at intervals 40 at the time of each longitudinal movement, means for slowly returning the pin to the former after each withdrawal, and automatic means for locking the pin in its returned position.
- 45 169. In a mechanical movement of the class described, the combination of a former and a former pin relatively movable longitudinally, means for effecting at intervals 50 relative longitudinal movements between the pin and former, automatic means for withdrawing the pin from the former at the time of each longitudinal movement, means for returning the pin to the former after each withdrawal, and automatic means for locking the pin in its returned position.
- 55 170. In a mechanical movement of the class described, the combination of a holder, a tool, automatic means for feeding the tool at intervals in a predetermined direction, means including a normally fixed former 60 and a former pin movable with the tool for causing the tool to follow a predetermined path, mechanism for withdrawing the tool from the said path and the former pin from the former before each movement, mechanism 65 acting entirely independently of the last said mechanism for returning the tool to the said path and the former pin to the former after each longitudinal movement, and means for locking the tool and pin in 70 their returned positions.
- 75 In testimony whereof, I hereto affix my signature.

FRIEDERICH MÜLLER.

Certificate of Correction.

It is hereby certified that in Letters Patent No. 1,429,612, granted September 19, 1922, upon the application of Friederich Müller, of Hartford, Connecticut, for an improvement in "Mechanical Movements," errors appear in the printed specification requiring correction as follows: Page 1, line 31, for the compound word "work-holder" read *work-holding*; page 13, line 65, claim 72, for the article "the" read *a*; page 16, line 59, claim 98, and page 17, line 74, claim 114, after the word "movement" insert a comma; page 18, lines 68 and 69, claim 124, after the word "carriage" insert a comma; and that the said Letters Patent should be read with these corrections therein that the same may conform to the record of the case in the Patent Office.

Signed and sealed this 28th day of November, A. D., 1922.

[~~SEAL~~]

KARL FENNING,

Acting Commissioner of Patents.
